SPARK RETARDING DEVICE

Application filed November 2, 1931. Serial No. 572,579.

This invention relates to a spark retarding device adapted to be used in connection with the usual ignition timing mechanism for effecting an extreme retardation of the spark when the engine is idling.

In the operation of an internal combustion engine equipped with the usual timer, in order to secure a smooth and steady performance when the engine is idling, the timer must be initially set so that the spark will occur when the crank is 5° to 10° past dead center. With such setting however, when the throttle is initially opened, if the advance of the timing depends directly or indirectly upon the engine speed, the pick-up will necessarily be slow. On the other hand, if the spark is initially set where it should be for the best performance immediately after the throttle is opened, the idling operation of the engine will be unsteady or will perhaps stop altogether.

With the above facts in mind, it is an object of the present invention to provide, in addition to the usual timer controlling means, a supplementary control device which is effective to cause an extreme retardation of the spark when the throttle is in idling position but is immediately rendered ineffective as the throttle begins to open. This supplementary control device, in the present embodiment of the invention, comprises a solenoid which is adapted to be energized only when an extreme retardation of the spark is desired, as for example, when the throttle is in idling position. When thus energized the solenoid causes the circuit breaker or breakers to be advanced in the direction of rotation of the cam so as to cause the desired extreme retardation of the spark, but when the circuit through the solenoid is opened, the spark will be immediately advanced to the normal setting regardless of any other conditions.

The present invention will be more particularly described in connection with the accompanying drawing, in which—

Figure 1 is a wiring diagram of the primary ignition circuit with parts of the control device shown in plan or in section;

Figure 2 is a similar view showing a modified form of the invention; and

Figure 3 is a vertical central section through the timer.

As shown in the drawing, the invention is associated with an ignition timer comprising a housing 5 formed with a bearing 6 for the timer shaft 7. A sleeve 8 is mounted for relative circumferential movement on the shaft 7 and is provided with a cam 9 for actuating the circuit breaker or breakers. The invention may be associated with any of the usual timer mechanisms. In the present instance, I have shown the timer as having two circuit breakers 10 and 11 respectively, mounted on studs 12 and 13 which project upwardly from a plate 14 mounted within the housing 5. These circuit breakers 10 and 11 are set so that their closure periods overlap, thus increasing the total period during which a current passes through the primary coil and thereby increasing the saturation and insuring a hot spark.

The relative position of the sleeve 8 and cam 9 with reference to the timer shaft 7 is controlled through the medium of a plate 15 which is secured to the sleeve by screws 16 or other suitable means and advanced circumferentially by means of a centrifugal governor 17 as the speed increases. Other suitable means may, however, be employed to adjust the timing for the higher speeds.

It will be understood that when the engine is operating, the primary ignition circuit is from the battery 18 through the ignition switch 19, spark coil 20 and line 21, thence through the circuit breakers and ground back to the battery, one branch being through post 22, spring 23, contacts 24 and grounded post 25, the other branch being through the post 26, spring 27, contact points 28 and grounded post 29.

Normally the timer will be set so that at low speeds the spark will occur when the crank is 5° to 10° past dead center and will be gradually advanced upon a predetermined increase in speed of the engine.

In accordance with the invention, provision is made for causing an extreme retardation of the spark, independently of the other control mechanism, by advancing the housing 5, together with the circuit breakers,

in the direction in which the cam 9 is rotating as indicated by the arrow in Figs. 1 and 2, thus causing an extreme retardation of the spark. In effecting this movement of the 5 housing 5, the latter is provided with an arm 30 which has a connection 31 with the core 32 of a solenoid 33. One terminal of the solenoid is connected to the ignition circuit, preferably between the switch 19 and the coil 10 20, and the other terminal is connected by a line 34 to a post 35 which is mounted in an insulating bushing 36.

In the form of the invention shown in Fig. 2, the post 35 is located on or near the 15 intake manifold 37. The throttle valve 38 is secured to a pivot pin 39 to which there is secured a crank arm 40 connected with a throttle control rod 41. The crank 40 is provided with a contact 42 which engages the 20 post 35 and completes a circuit through the solenoid 33 only when the throttle valve is in position for idling. When the solenoid 33 is thus energized, the core 32 moves to the left as indicated in the drawing and moves the 25 housing 5 and circuit breakers 10 and 11 in a direction to cause an extreme retardation of the spark.

In the form of the invention shown in Fig. 1, the post 35 is mounted in the end of a 30 cylinder 43, which is connected by a conduit or nipple 44 with the intake manifold 37. A piston 45 within the cylinder 43 has a stem 46 which is adapted to contact with the post 35 to complete a circuit through the solenoid 33. 35 The piston 45, however, is normally held by a spring 47 in a position to prevent the completion of the circuit through the solenoid except when the throttle valve is in idling position. In order to effect this result, the 40 spring 47 is so tensioned that only the high vacuum developed in the manifold when the engine is idling will be sufficient to overcome the tension of the spring and bring the stem 46 into contact with the post 35. Under the 45 usual operating conditions, if the throttle is partially or wholly open there will not be as high a degree of vacuum in the manifold as is the case when the throttle is in closed or idling position.

50 From the foregoing description, it will be understood that, with a proper setting of the timer, whenever the engine is idling, there will be an extreme retardation of the spark 55 which will insure a smooth performance. As soon as the throttle begins to open, however, the spark will be immediately advanced to a proper position for insuring a quick pick-up and as the speed of the engine increases, the advance of the timing will be controlled in the usual normal manner.

It will be apparent that the invention may be incorporated in various other types of timers and that the arrangement may be modified in other ways without departing from 60

the scope of the invention as defined in the claims.

What is claimed is:

1. In an ignition timing device, a primary circuit including a circuit breaker for controlling the timing of the ignition, a solenoid operable, when energized, to cause an extreme retardation of the timing, and means shiftable under the influence of suction in the engine intake to energize the solenoid. 75

2. In an ignition timing device, a primary circuit including a circuit breaker for controlling the timing of the ignition and means to automatically advance the timing according to the speed, a solenoid operable when energized, to cause an extreme retardation of the timing, and means shiftable under the influence of suction in the engine intake to energize the solenoid. 80

3. In an ignition timing device, means operable by itself to automatically control the timing in accordance with operating conditions, a solenoid operable, when energized, to modify the result of said means, and means shiftable under the influence of suction in the engine intake to energize the solenoid. 85

4. In an ignition timing device, means operable by itself to automatically control the timing in accordance with operating conditions, a solenoid operable, when energized, to retard the spark with reference to the timing effected by said means, and means shiftable under the influence of suction in the engine intake to energize the solenoid. 95

5. In an ignition timing device, a primary circuit including a circuit breaker for controlling the timing of the ignition, a timer shaft, a cam mounted on the shaft for actuating the circuit breaker, means for automatically shifting the cam with reference to the 100 shaft to vary the time of ignition in accordance with operating conditions, a solenoid operable, when energized, to shift the circuit breaker in a direction to retard the timing, and means shiftable under the influence of 105 suction in the engine intake to energize the solenoid. 110

6. In an ignition timing device, a primary circuit including a circuit breaker for controlling the timing of the ignition, a timer shaft, a cam mounted on the shaft for actuating the circuit breaker, means for automatically shifting the cam with reference to the shaft to vary the time of ignition in accordance with operating conditions, a solenoid 115 operable, when energized, to shift the circuit breaker in a direction to retard the timing, and means rendered effective, whenever the engine is idling, to close a circuit through 120 said solenoid to energize the same. 125

7. In an ignition timing device, a primary circuit including a circuit breaker for controlling the timing of the ignition, a solenoid operable, when energized, to cause an extreme retardation of the timing, and means ren- 130

- dered effective, whenever the engine is idling, to energize said solenoid.
8. In an ignition timing device, a primary circuit including a circuit breaker for controlling the timing of the ignition, and means to automatically advance the timing according to the speed, a solenoid operable, when energized, to cause an extreme retardation of the timing, and means rendered effective, whenever the engine is idling, to close a circuit through said solenoid to energize the same.
9. In an ignition timing device, means operable by itself to automatically control the timing in accordance with operating conditions, a solenoid operable, when energized, to modify the result of said means, and means rendered effective, whenever the engine is idling, to energize said solenoid.
10. In an ignition timing device, means operable by itself to automatically control the timing in accordance with operating conditions, a solenoid operable, when energized, to retard the spark with reference to the timing effected by said means, and means rendered effective, whenever the engine is idling, to energize said solenoid.
11. In an ignition timing device for internal combustion engines, a primary circuit including a circuit breaker for controlling the timing of the ignition, a solenoid operable, when energized, to cause an extreme retardation of the timing, and means connected with the throttle to close the circuit through the solenoid whenever the throttle is shifted to idling position.
12. In an ignition timing device for internal combustion engines, a primary circuit including a circuit breaker for controlling the timing of the ignition, means tending to automatically advance the timing according to the speed of the engine, a solenoid operable, when energized, to cause an extreme retardation of the timing, and means connected with the throttle to close the circuit through the solenoid whenever the throttle is shifted to idling position.
13. In an ignition timing device for internal combustion engines, means operable by itself to automatically control the timing in accordance with operating conditions, a solenoid operable, when energized, to modify the result of said means, and means connected with the throttle to close the circuit through the solenoid whenever the throttle is shifted to idling position.
14. In an ignition timing device for internal combustion engines, means operable by itself to automatically control the timing in accordance with operating conditions, a solenoid operable, when energized, to retard the spark with reference to the timing effected by said means, and means connected with the throttle to close the circuit through the sole-
- noid whenever the throttle is shifted to idling position.
15. In an ignition timing device for internal combustion engines, a primary circuit including a circuit breaker for controlling the timing of the ignition, a timer shaft, a cam mounted on the shaft for actuating the circuit breaker, means for automatically shifting the cam with reference to the shaft to vary the time of ignition in accordance with operating conditions, a solenoid operable, when energized, to shift the circuit breaker in a direction to retard the timing, and means connected with the throttle to close the circuit through the solenoid whenever the throttle is shifted to idling position.
- In testimony whereof I have hereunto signed my name to this specification.
- MARION MALLORY.
